RESILIENT HEEL

Filed Aug. 13, 1929

Inventor

Benjamin Kind

UNITED STATES PATENT OFFICE

BENJAMIN KIND, OF BALTIMORE, MARYLAND

RESILIENT HEEL

Application filed August 13, 1929. Serial No. 385,526.

This invention relates to footwear and more particularly to the sole and heel thereof.

The conventional types of leather or rubber heels and soles employed in footwear at the present time possess numerous disadvantages, primarily due to the material and manner in which they are made. Heels and soles made of leather are hard, non-shock absorbing, heat conducting as regards extremes of temperature and in most cases non-waterproof. On the other hand, heels and soles made up of rubber, while obviating the disadvantages inherent in heels and soles made of leather to a certain extent, are nevertheless far from being satisfactory, it being well known that the wearing of footwear having solid rubber heels and soles is extremely uncomfortable.

The object of this invention is to provide a heel or sole, made of rubber or any other suitable material and embodying within its structure a hermetically sealed bag or tube containing air under pressure, whereby the same will render said heel and sole extremely resilient and shock absorbing, waterproof, and due to the layer of "dead" air therein the degree of heat conductivity under extremes of temperature will be practically reduced to a minimum.

Another object of this invention is to provide a heel and sole of this character which is low in cost, capable of being easily manufactured, easy to apply to a shoe and easy to replace.

Other objects of this invention will become apparent as the description thereof, given hereunder, proceeds, reference being now had to the accompanying drawing, wherein:—

Fig. 1 is a top plan view of the heel,

Fig. 2 is a detail plan view of the interior of the heel taken on line 2—2, Fig. 3, and

Fig. 3 is a sectional elevational view of the heel taken on line 3—3, Fig. 1.

The heel 1, constituting part of my invention, is made conventional in shape and of suitable material and comprises essentially a resilient housing comprising a top 2 and a wall 3 integrally molded therewith and extending completely around the periphery of

said top portion as clearly shown in Fig. 2, said wall 3 being of uniform thickness and depth throughout. If desired the top portion 2 and the wall 3 may be made separate and of different material. Formed integral 55 with the wall 3 at spaced intervals thereof and extending inwardly, in the recess formed by said wall, are a plurality of lugs 4. At each of said lugs 4, and the corners 5 and 6 of the heel, holes 7 are provided for a purpose to be hereinafter described, said holes extending through the entire depth of the wall 3. Each of said holes 7 are countersunk as at 8 on the top 2 of the heel 1. Positioned substantially centrally within the interior of 60 the heel 1, and molded integral with the top 2 is a depending boss 9, provided with a central hole or bore 7', countersunk at its upper end as at 8'; the bottom of said boss 9 being 65 in the same plane with the bottom of the side-wall 3, as clearly shown in Fig. 3.

In the space or recess formed between the boss 9 and side wall 3 is inserted a substantially annular resilient inflated member 10, somewhat on the order of an inner tube. The 75 annular member 10 comprises a hermetically sealed rubber tube containing air under pressure, sufficient to withstand the weight of a person without collapsing. The top 2 of the heel is preferably moulded with an annular 80 convex-concave bulge 11 on its upper surface conforming to the shape of the annular resilient member 10 which is seated in the concave portion of said bulge as shown in Fig. 3.

A cover plate 12 made of either rubber or 85 leather and of the same general contour as the heel proper is vulcanized or otherwise secured to the bottom edge of the wall 3 and boss 9 of said heel, said cover plate being provided with holes 7" adapted to align with the holes 90 7 in the wall 3, and the hole 7' in the boss 9.

The heel 1 as above constructed is adapted to be handled as a unit. When applied to a shoe, the cover plate 12 of the heel 1 engages the bottom of the shoe, said heel being secured thereto by means of nails inserted through the holes 7 and 7'. The heads of said nails (not shown) being driven beneath the surface of the top 2 in the manner well known in the art. 100

I claim:—

An elastic heel of resilient material comprising a top portion having an annular concave-convex bulge moulded thereon, a wall of uniform depth and thickness extending around the entire periphery of said top portion and integral therewith, a plurality of spaced inwardly extending lugs integral with the interior of said wall and each having a vertical hole therein, a centrally disposed vertical boss integral with the interior of said top portion, an annular tube of resilient material containing air under pressure positioned in said heel and adapted to seat in said concave bulge, and a flat cover plate for said heel adapted to engage the edge of said wall, the end of said vertical boss, and the top of said tube.

In testimony whereof I affix my signature.

BENJAMIN KIND.
